United States Patent Office.

A. N. KELLOGG, OF CHICAGO, ILLINOIS.

Letters Patent No. 98,269, dated December 28, 1869.

IMPROVED ROTARY TABLE-WAITER.

The Schedule referred to in these Letters Patent and making part of the same

To all whom it may concern:

Be it known that I, A. N. KELLOGG, of Chicago, in the county of Cook, and State of Illinois, have invented a new and useful Improved Rotary Table-Waiter; and I do hereby declare the following to be a full, clear, and exact description thereof, which will enable others skilled in the art to make and use the same, reference being had to the accompanying drawings, forming part of this specification, in which—

Figure 1 is a transverse vertical section of my improved table-waiter, taken in the line $z z$, fig. 2;

Figure 2 is a top plan view of the same;

Figure 3 is a transverse vertical section of a modification; and

Figure 4 is a top plan view of fig. 3.

Similar letters of reference indicate corresponding parts in the several figures of the drawings.

My invention has for its object to provide a portable table-waiter, by which articles of food can easily be obtained from different parts of the table, without the aid of a servant, and without interruption to conversation. To this end,

My invention consists, first, in providing the portable stand with a vertically-adjustable rotary-frame, adapted to receive caster-bottles and dishes, either or both, in such a manner as to present them to all sides of the table.

It consists, further, in the combination of the rotary dish-holding plate, and the rotary adjustable frame, upon the same stand, as will be hereinafter more fully described.

In the accompanying drawings—

A is a vertical shaft, mounted upon the base B, forming a stand similar to those employed for table-caster, with the exception of being much larger.

C is a horizontal plate, or disk, mounted upon the shaft A, near the base B, and adapted to be rotated freely. This plate is designed to receive one or more dishes, usually the lighter and smaller dishes of the table.

When, however, larger dishes are used, the plate will be supported and allowed to rotate freely by means of the rollers a, upon its under surface, bearing upon the top of the table.

It will be readily understood, that whenever any particular dish is required, plate C is rotated until such dish is brought within reach.

Thus every person at the table can serve themselves, without interruption of conversation, and without requiring the aid of a servant.

I do not intend to confine myself to any special form of the rotary plate C, as this may be varied indefinitely.

In fig. 4, a series of disks, C, is shown, supported upon suitable arms mounted upon shaft A.

D is a frame, composed of a series of radial arms, E, and mounted upon the shaft A in such a manner as to rotate thereon.

The ends of the arms E are bent upward, and one or more provided with suitable receptacles, F, for caster-bottles.

These receptacles are either rigidly affixed to the arms, or adapted to be rotated thereon, as shown at b, fig. 3.

G are disks, or plates, also mounted upon one or more of the arms, E, and are adapted for the reception of sugar-bowls, cream-pots, &c., or the reception of a tea-cup or plate for transit.

The frame D is adjustable vertically upon the shaft A, by means of the collar d upon the latter, and the set-screw f, for the purpose of accommodating the different height of articles placed upon the rotary plate C.

For example, if bottles are placed upon the plate C, it will be necessary to raise the frame D sufficiently to clear such bottles, and allow rotation of both the frame and plate. When articles of lesser height are in use, the frame D may be lowered.

For the purpose of facilitating cleaning or packing for transportation, the shaft A and base B are screwed together, and may therefore be separated, and also permit the removal from the shaft of the plate C and frame D. By this construction, all the parts can be separately packed, with much economy of room.

My improved table-waiter is not only of great utility, but forms a pleasing ornament to the table.

It is simple and cheap in construction, and supplies a want long felt among housekeepers and others.

It will be found of great advantage to those families whose means will not permit of a dining-room servant.

Having thus described my invention,

What I claim as new, and desire to secure by Letters Patent, is—

1. The rotary frame D, adapted for adjustment vertically upon the shaft A, as herein shown and described, for the purpose specified.

2. The combination of a rotary dish-holder C, and a rotary adjustable dish and bottle-holding frame D, upon the same stand, as herein shown and described, for the purpose specified.

The above specification signed by me, this 6th day of September, 1869.

A. N. KELLOGG.
